UNITED STATES PATENT OFFICE.

CLARENCE OTTO THROP, OF JEFFERSON, IOWA.

VALVE-REMOVER.

1,208,406.

Specification of Letters Patent. Patented Dec. 12, 1916.

Application filed March 31, 1915. Serial No. 18,404.

To all whom it may concern:

Be it known that I, CLARENCE OTTO THROP, a citizen of the United States, and resident of Jefferson, in the county of Greene and State of Iowa, have invented a certain new and useful Valve-Remover, of which the following is a specification.

The object of my invention is to provide a valve remover of simple, durable and inexpensive construction.

A further object is to provide a valve remover adapted to be used on internal combustion engines, or motor vehicles, and so arranged and constructed that part of the tool may remain fixed in position with relation to an engine, while the other part may be moved for raising the valve spring, or compressing it in such a way as to permit ready access to parts of the valve stem.

My invention consists in the construction, arrangement and combination of the various parts of the device whereby the objects contemplated are attained as hereinafter more fully set forth, pointed out in my claim and illustrated in the accompanying drawings, in which:

Figure 1 shows a side elevation of a valve removing tool embodying my invention, parts of the engine being shown in section. Fig. 2 shows a horizontal sectional view taken on the line 2—2 of Fig. 1, the dotted lines showing the shape of the opening in the part of the tool, which raises the spring. Fig. 3 shows an inverted plan view of the cam lever, and Fig. 4 shows a side elevation of a modified form of my invention, as applied to a valve.

It is well known to mechanics who work in automobile repair shops and factories, that it is difficult to remove the valves of an internal combustion engine for grinding. Satisfactory tools for removing the valves have been unknown. The difficulty will be understood from a very brief explanation of the removal of a valve. The valve in Ford cars for instance, has a stem which engages a tappet or additional stem operated by a cam. Frequently the valve stem has a collar or its equivalent held by a pin extended through the collar and the stem. The spring must be contracted away from the collar and the pin, in order to remove them to make it possible to remove the valve for grinding.

On different engines the valves are differently arranged with relation to the body of the engine, and it may be said that the

same tool will not ordinarily serve for compressing the springs of engines of different types. My improved valve removing tool is designed to obviate these difficulties, and is adapted to be used with a variety of types of engines.

In the accompanying drawings, I have used the reference numeral 10 to indicate the parts of the engine having the valve 11 on the seat 12. The valve 11 has the stem 13, on which is a collar 14 held in position by a pin 15. On the stem 13 is a spring 13a.

It will be noted that in the type of engine partially illustrated in the drawings, the part 10a of the engine frame or body extends outwardly over the valve. Above the valve, in the type of engine shown in Fig. 1, is an opening 16, ordinarily closed in some suitable way when the engine is in use.

In Figs. 1, 2, and 3 I have shown one form of my improved valve removing tool, which will now be described. In this connection it may be mentioned that while I have described my tool as used for a valve with a stem vertically arranged, that my tool can be used with valves arranged horizontally.

The form of my tool shown in Fig. 1 comprises a vertical member 17, having in its upper portion a plurality of spaced openings 18. At the lower end of the member 17 is a laterally extending member 19 having a flat horizontally enlarged portion 20 at its end, provided with an opening 21, illustrated by dotted lines in Fig. 2, having a narrow neck as shown.

Slidably mounted on the vertically arranged arm 17 is a laterally extending arm 22 parallel with the arm 19, having at its free end a downward extension 23, the lower end of which is adapted to engage some portion of an engine and remain fixed in position during the operation of the tool. As illustrated in the drawing, the lower end of the portion 23 engages the valve.

In connection with the parts just described, there is provided a lever 24, having a substantially right angled extension 25 composed of two parallel arms. In the ends of the arms 25 are openings 26 which register with each other. The arms 25 are adapted to be secured to the member 17 by extending a pin 27 through the openings 26 and selectively mounting the pin 27 in one of the openings 18. The arms 25 are provided with parallel cam faces 28, and the portion 24 is provided with a flat portion 29 adapted

to engage the upper surface of the arm 22 for locking the parts in position, as will be hereinafter described.

I shall now describe the practical operation of the form of my device illustrated in Figs. 1 to 3 inclusive. The tool being approximately adjusted for use on the particular size and type of engine from which the valves are to be removed, by selectively 10 mounting the pin 27 in the proper hole 18, the lever is raised to its position shown by dotted lines in Fig. 1, the extension 23 is then placed on top of the valve, as illustrated, while the portion 20 of the member 15 is inserted beneath the spring. In this connection attention is called to the fact that sometimes there is a washer below the spring, and that the extension 20 is actually 20 in contact with the washer and not with the spring. The operation, however, of the tool is the same whether the portion 20 engages the washer or the spring. The handle 24 is then swung outwardly and downwardly, whereby the cam face 28 is forced against 25 the upper surface of the arm 22, thereby drawing the members 17, 19 and 20 upwardly and contracting the spring 13^a, and removing its lower end from the collar 14 and pin 15. The parts are so arranged that 30 when the lever 24 is swung downward to substantially horizontal position, as illustrated by the full lines in Fig. 1, the flat portion 29 engages the upper surface of the arm 22, so that when a load is imposed on 35 the tool by the contraction of the spring, the parts are locked in the position, shown in Fig. 1. The operator may then leave the tool standing in its locked position, and remove the pin 15, which makes it possible to 40 slide the collar 14 on the valve stem, after which the removal of the valve is an easy matter.

In Fig. 4, I have shown a modified form of my improved valve removing tool, comprising a bar 30 having parallel upwardly extending spaced lugs 31, provided with registering openings 32. The end 33 of the arm 30 is substantially the same construction as the end 20 of the extension 19. 45 Pivoted between the lugs by means of a pin 34 extended through the openings 32 is a lever arm 35, the free end 36 of which is constructed substantially like the member 20.

Pivoted to the arm 35 is a lever 37 extending downwardly from the arm 35 and having a handle 38 extending upwardly and away from the lever 37 in the opposite direction from the end 36. The lever 37 has a cam face 39, adapted to fit in a groove 40, shown by dotted lines in Fig. 4, and a portion 41 adapted to extend into said groove

and to lock the parts in position, after the lever has been operated.

In the practical operation of the form of the tool shown in Fig. 4, the end 33 is placed 65 on the valve tappet 44 below the collar 14, the lever 38 is raised to substantially vertical position, and the end 36 is placed just below the spring 13^a. The arm 38 is then swung outwardly and away from the spring, 70 causing the cam face 39 to engage the arm 30, and to force the end 36 away from the end 33, thereby raising the spring 13^a away from the end 33. When the handle 38 reaches its substantially horizontal position, as illustrated 75 in Fig. 4, the parts are locked and the operator can then remove the pin 15, for thereby loosening the collar on the stem 13.

It will be understood that some changes 80 may be made in the construction and arrangement of the parts of my improved valve remover without departing from its essential features and purposes, and it is my intent to cover by this application any such 85 changes which may be included within the scope of the following claim.

I claim as my invention.

A valve remover comprising an upright member provided with a plurality of spaced 90 openings, a lateral extension at the lower end of said member having forked ends adapted to receive a flat stem between them, a laterally extending arm slidably but non-rotatably mounted on said upright member 95 parallel with said extension, having at its free end a downwardly extending member arranged to be above the space between the forked arms of said extension, a lever arm having a bifurcated curved end provided 100 with cam faces, the bifurcated end members being provided with registering openings, and a bolt detachably extended through said last openings and selectively received in one of the openings in the upright member, said 105 lever arm and bifurcated end portions thereof having a flat portion designed to rest immediately above said laterally extending arm and to engage the same, with said flat portion substantially in line with the upper 110 surface of said arm when the lever arm is in one position of its movement and to be swung upwardly to position adjacent to the upper end of said upright member with said bifurcated end above the laterally extending 115 arm in another position of said lever.

Des Moines, Iowa, March 12, 1915.
